UNITED STATES PATENT OFFICE.

JEREMIAH VANDERBILT, OF BROOKLYN, NEW YORK, ASSIGNOR TO ROBERT LEFFERTS, OF SAME PLACE.

DESIGN FOR A CANDLE-SHADE.

SPECIFICATION forming part of Design No. 26,787, dated March 23, 1897.

Application filed February 4, 1897. Serial No. 622,051. Term of patent 7 years.

To all whom it may concern:

Be it known that I, JEREMIAH VANDERBILT, a citizen of the United States, residing at Brooklyn, county of Kings, and State of New York, have invented and produced a new and original Design for Candle-Shades and the Like, (Case B) of which the following is a specification.

My invention relates to a design for a candle or lamp shade; and it consists in the configuration and disposition of parts substantially as illustrated in the accompanying drawings, forming part of this specification, in which—

Figure 1 is a plan view. Fig. 2 is a side elevation, and Fig. 3 a sectional elevation.

The design consists of a series of flowers disposed in concentric rings at the base and apex of a truncated cone-like figure, with petal-like pieces extending between the rings of flowers, and from the base of the cone depends a fringe.

The cone-like base 1 of the shade, which has a crinkled surface, is provided with a thick and annular base-piece 2. At the top of the base 1 is a conical ring 3, surmounted by an annular ring 4.

The foregoing serves as a support and outline giving body for the disposition of the circles of flowers and intervening petal-like pieces.

At 5 are the lower flowers, secured upon the base 1 adjacent the ring or base-piece 2 and extending bodily outward therefrom, as shown in Fig. 3, and at 6 are the upper flowers, forming the upper ring, secured to the base-piece 1, adjacent the inner ring 4, the petals of which extend upwardly above said ring, as shown in Fig. 3.

Secured to the base-piece 1 and extending between the petals of the upper and lower rings of flowers are the petal-like pieces 7, formed by folding over a suitable piece of fabric or the like upon itself, the free edges of which overlap the folded edge, which petal-like pieces cover the base-piece 1, the upper and lower ends of the pieces being covered by the upper and lower petals of the upper and lower rings of flowers, as clearly illustrated in the figures.

Depending from the base-piece 2 and secured exteriorly thereto is a circular band of fringe 8.

Having described my invention, I claim—

The design for a candle-shade or the like, substantially as herein shown and described.

Signed at the city, county, and State of New York this 30th day of January, 1897.

JEREMIAH VANDERBILT
